UNITED STATES PATENT OFFICE

2,340,193

RECEIVING HOPPER STRUCTURE FOR HOT METAL MIXERS

Harry L. McFeaters, New Castle, Pa., assignor to Pennsylvania Engineering Works, a corporation of Pennsylvania

Application March 15, 1943, Serial No. 479,209

5 Claims. (Cl. 266—39)

This invention relates to hot metal mixers and more particularly to hopper structures for the charging openings of such mixers.

In hot metal mixers of the type in which the top portion of the mixer shell is provided with at least one charging opening, and the refractory lining of the shell is provided with an opening below such charging opening, the shell opening is usually surrounded by an upstanding member which, as in Patent 1,771,241 of July 22, 1930, forms a support for a removable hopper forming member or thimble which is provided with refractory lining.

This construction permits replacement of the hopper by another relined hopper as its refractory lining becomes eaten away or eroded by the molten metal as it is charged into the mixer through the hopper.

In these prior mixers, the wall of the hole or opening in the refractory lining below the charging opening is also eaten away by erosion and requires frequent replacement.

Replacement of this wall is a more or less difficult job and one object of this invention is to produce a hopper structure in which such wall forms part of the hopper structure and is therefore removable with the hopper.

Another object is to produce a hopper structure in which such wall is water cooled in order to give it a longer useful life.

A further object is to produce a hopper structure in which such wall forms part of the hopper structure, so that as the refractory parts of such structure become eroded, the hopper can be replaced with another hopper in which the refractory parts have been renewed or repaired.

A further object is to produce a removable hopper for the charging opening having a refractory skirt which is water cooled and which extends through the opening in the mixer lining below the hopper.

A still further object is to produce a removable hopper for the charging opening having a water cooled refractory skirt which extends through the opening in the mixer lining below the hopper, and which is removable with the hopper.

These and other objects, which will be apparent to those skilled in the hot metal mixer art, I attain by the hopper structure described in the specification and illustrated in the drawings accompanying and forming part of this application.

In the drawings:

Figure 1 is a view partially in section and partially in elevation of a hot metal mixer equipped

with a charging opening hopper embodying this invention. In this view, the supporting and tilting apparatus for the mixer has been omitted.

Fig. 2 is an enlarged detail view of the charging opening hopper structure of this invention; and

Fig. 3 is a fragmentary sectional view on an enlarged scale of a portion of the cooling element for the refractory skirt of the hopper structure.

10 In Fig. 1 of the drawings, I have disclosed one type of hot metal mixer to which the invention of this application is applicable. This mixer comprises an outer shell 5, having a charging hopper 6, a pouring spout 7, a connecting portion 8 leading from the mixer proper to pouring spout 7, a refractory lining 9 for the major portion of the mixer, preferably formed of refractory bricks which closely fit the mixer shell, and the top refractory lining 10 which is preferably spaced from the top of the mixer shell, a refractory lining 11 for channel portion 8, and a refractory lining for spout 7, which lining is not shown.

15 The upper lining 10, which constitutes the roof portion of the mixer lining, is preferably formed as a sprung arch supported on skewblocks 12 and 13. The supporting structure for the mixer shell and the apparatus for tilting the shell to and from pouring position has been omitted for the purpose of simplification.

20 The mixer illustrated is of the barrel type and one or both ends of the same may be provided with inspection openings 14 and a burner opening 15 in the refractory lining and with suitable covers for the inspection openings in the shell ends.

25 The mixer shell which is preferably formed of suitable metal plate sections connected together as by welding, is provided with a circular charging opening 16 (Fig. 2) and the arch or roof 10 below the charging opening is provided with a circular opening bounded by arch or roof bricks 17. Opening 16 is surrounded by an upstanding support member. This member is of welded construction and comprises a cylindrical member 18 having an upper flange 19 and a lower flange 20, which is welded to the shell around the charging opening.

30 A cast metal hopper comprising a cylindrical body portion 21, an upper outwardly extending flange 22 and a lower inwardly extending flange 23 is removably supported in place on the upper flange of the support member.

35 The hopper is provided with a refractory lining 24. A hollow annular metal member 25 is

secured in place below and in contact with inwardly extending flange 23.

Member 25 is preferably formed of steel tubing which is flattened as shown in the drawings and is bent into the form of a ring with its ends welded to a plate-like member 26 which forms a baffle in the annular chamber between inlet pipe 27 and outlet pipe 28. These pipes enter the top portion of member 25 and are welded in place as disclosed at 29, Fig. 3. From this construction, it will be apparent that cooling water or other cooling fluid entering inlet pipe 27 will circulate through member 25 and pass out through outlet pipe 28.

Pipes 27 and 28 pass upwardly through openings such as opening 30 formed in flange 23 of the hopper. The upper ends of each of these pipes, by means of elbows 31 connect with pipes such as 32 which are part of a cooling water or other cooling medium circulating system.

Member 25, at its top, bears against the under face of the lower flange of the hopper and is securely held in place by angle clips or brackets 33 which are welded to the under face of said flange and to member 25. A bar-like member 34, preferably of round section, is welded to the inner peripheral face of member 25 and forms an anchor for an annular refractory skirt member 35. This skirt is preferably formed of refractory material, while the same is in plastic condition and before the hopper and water cooler 25 are placed in position within the charging opening. Anchor member 34 securely holds the refractory skirt member in place.

The refractory bricks which surround the opening in the mixer lining below the hopper are cut away to accommodate annular water cooler 25 as disclosed in Fig. 2 and the refractory skirt is preferably of such length as to extend from the lower face of flange 23 to the lower face of arch or roof 40. The space between the skirt and the lower edge of the refractory lining of the hopper is filled with plastic refractory material 36.

Before lifting the hopper from position, it will be necessary to unscrew pipes 32 from elbows 31.

A cast cover 37 lined with refractory material 38 is provided for the hopper and this as shown in the drawings, is supported in position by refractory lining 24 of the hopper. A system of links and levers as shown in Fig. 2 of usual construction is utilized for moving the cover to and from closing position.

Having thus described my invention, what I claim as new and desire to secure by Letters Patent is:

1. In combination in a hot metal mixer having a shell provided with a charging opening surrounded by an upstanding support member and a refractory lining for the shell having an opening below said charging opening, a removable metal hopper supported by said support member and having a refractory lining, an annular refractory member below said hopper member, forming a refractory skirt for the hopper member which extends into the opening in the shell lining, and means connecting such

skirt to the hopper; the construction and arrangement being such that said skirt forms part of the hopper and is removable with the same.

2. In combination with the shell of a hot metal mixer having a charging opening surrounded by a support member and a refractory lining for said shell having an opening below said charging opening, a removable metal hopper member supported by said support member and extending through the charging opening, a refractory lining for said hopper member, an annular refractory member below said hopper member and extending into the opening within the shell lining, and a hollow metal member secured to and depending from said hopper member and having a cooling medium inlet and a cooling medium outlet and being constructed and arranged to support said annular refractory member.

3. In combination with the shell of a hot metal mixer having a charging opening surrounded by an upstanding member supported by said shell and a refractory lining for said shell having an opening below said charging opening, a removable metal hopper member supported by said upstanding member, extending through the opening in the shell and, adjacent its bottom having an inwardly extending flange, a refractory lining for such hopper member supported by said flange, a refractory skirt located below said flange and extending into the opening in the shell lining, and a cooling element located below and secured to said hopper member, having a fluid inlet and a fluid outlet, contacting with and surrounding said refractory skirt and carrying means for anchoring said skirt in place.

4. In combination with the metal shell of a hot metal mixer having a charging opening surrounded by a support member and a refractory lining having an opening below said charging opening, a removable metal hopper supported by said support member, extending through the charging opening in said shell and adjacent its bottom having an inwardly extending flange, a refractory lining for the hopper carried by said inwardly extending flange, a skirt-like refractory member below said flange, a flattened tubular metal ring secured to said flange, depending from the same, having an inlet and an outlet for a cooling medium and provided on its inner peripheral face with means for anchoring said skirt-like refractory member in place.

5. In combination with the metal shell of a hot metal mixer having a charging opening surrounded by an upstanding support member, and a refractory lining for said shell having an opening below said charging opening, a removable hopper having a refractory lining, an annular refractory skirt below said hopper, and extending into the opening in the shell lining, and a hollow annular metal water cooled member secured to and depending from said hopper, surrounding said skirt, anchoring said member in place and having an inlet and an outlet for cooling water.

HARRY L. McFEATERS.

CERTIFICATE OF CORRECTION.

Patent No. 2,340,193.

January 25, 1944.

HARRY L. McFEATERS.

It is hereby certified that error appears in the printed specification of the above numbered patent requiring correction as follows: Page 2, second column, line 63, claim 5, for "member" read --skirt--; and that the said Letters Patent should be read with this correction therein that the same may conform to the record of the case in the Patent Office.

Signed and sealed this 14th day of March, A. D. 1944.

Leslie Frazer

Acting Commissioner of Patents.
